Primary Examiner — Mojtaba Tehrani(74) *Attorney, Agent, or Firm* — Law Office of Arthur M. Antonelli, PLLC(57) **CLAIM**

The ornamental design for a stock for a small arms weapon, as shown and described.

DESCRIPTION

FIG. 1 is a right side view of a stock for a small arms weapon in accordance with my new design, the left side view being a mirror image thereof;

FIG. 2 is a top view thereof;

FIG. 3 is a bottom view thereof;

FIG. 4 is a front view thereof;

FIG. 5 is a rear view thereof;

FIG. 6 is a top, rear, left side view thereof; and,

FIG. 7 is a bottom, front, right side view thereof.

The broken lines immediately adjacent the shaded areas depict the unclaimed bounds of the claimed design; all remaining broken lines disclose unclaimed portions of the stock for a small arms weapon only and form no part of the claimed design.
